UNITED STATES PATENT OFFICE

LLOYD C. DANIELS, OF CRAFTON, PENNSYLVANIA, ASSIGNOR TO THE SELDEN COMPANY, OF PITTSBURGH, PENNSYLVANIA, A CORPORATION OF DELAWARE

PURIFICATION OF BENZOIC ACID AND ITS DERIVATIVES

No Drawing.

Application filed April 8, 1929. Serial No. 353,677.

This invention relates to the separation of polycarboxylic acids from the corresponding monocarboxylic acids.

Various reactions for the splitting off of carboxyl groups from polycarboxylic acids have been developed and as a result the problem of separating polycarboxylic acids from the corresponding monocarboxylic acids has become acute because in the ordinary processes of splitting a reaction product is obtained which contains both the monocarboxylic acid desired and considerable quantities of unchanged polycarboxylic acid. Examples of mixtures are phthalic and benzoic acid and halogen, nitro-, amino- or thiophthalic and benzoic acids and hydrogenated derivatives; naphthalic and naphthoic acids and their substituted derivatives; diphenic and phenylbenzoic acid; maleic or fumaric and acrylic acid; etc.

According to the present invention the acids are separated by a process of partial neutralization taking advantage of the fact that the dissociation constant for one hydrogen of the polycarboxylic acid is normally greater and in some cases very much greater than the dissociation constant of the corresponding monocarboxylic acid. For example, the first dissociation constant of phthalic acid is 1.21×10^{-5} as compared to 6×10^{-5} for benzoic acid and even greater differences may be noted between maleic acid with a first dissociation constant of 1.17×10^{-2} as compared to acrylic 5.6×10^{-5} , and fumaric 9.3×10^{-4} . Similar conditions of varying orders of magnitude are to be noted in the case of other polycarboxylic acids and their corresponding monocarboxylic acids. When, therefore, sufficient base, usually alkali, is present to combine with only one carboxyl group of the polycarboxylic acid, this reaction will take place to the practically complete exclusion of salt formation of the monocarboxylic acid. Similarly, if a mixture of salts of the two acids are present and a strong mineral acid is added to neutralize the correct amount of base, this will result again in the production of a mixture of the monosalt of

the polycarboxylic acid and the free monocarboxylic acid.

After partial neutralization or acidification the mixture of the salt of the polycarboxylic acid and the free monocarboxylic acid can be readily separated because the two compounds show very different solubilities. In some cases the difference in solubility in water is sufficiently great to effect clean-cut separation. This is for example, the case with mixtures of phthalic and benzoic acids and with mixtures of naphthalic and naphthoic acids where the benzoic or naphthoic acid respectively is relatively insoluble in water. The monoalkali metal phthalate or naphthalate is, of course, soluble in water and a very easy separation is thereby obtained at low cost. The separation of maleic acid from acrylic acid, however, requires a different solvent as the solubility of acrylic acid in water is too great to permit of a clean cut separation. Therefore, a solvent such as ether may be used in which acrylic acid is fairly soluble, whereas the monosodium maleate or fumarate is practically insoluble. Of course a similar procedure could be used with benzoic acid and phthalic acid by choosing a solvent for benzoic acid, such as chloroform or benzol, but is normally not to be considered because wherever the monocarboxylic acid is relatively insoluble in water it is much cheaper to use water as a solvent. The invention, however, is not limited to using water as a solvent even in the case of such acids where water could be used but includes the use of any solvent in which the salt of the polycarboxylic acid and the free monocarboxylic acid possesses markedly different solubilities.

When water is used as a solvent and in some cases when organic solvents are used it should be borne in mind that the solubility of organic compounds is apt to be greatly effected by the presence of other soluble organic compounds. This is particularly true in the case of benzoic acid and it is, therefore, desirable to purify the mixture of the acids as much as possible before subjecting them to the present process. A purification by fractional sublimation and the like is fre-

quently helpful and cheap. The present invention, however, does not depend on the treatment of mixtures which have been previously purified but is generally applicable.

5 A few typical embodiments of the invention will be described in the following specific examples.

Example 1

10 A mixture containing 5 parts of benzoic acid and 15 parts of phthalic acid, which mixture is relatively free from other impurities, is dissolved in 150 c. c. of water. 5.3 parts of sodium carbonate, corresponding to 98% of the amount required to convert the 15 phthalic acid to the primary sodium salt, are added and the mixture is chilled to 7° C., the benzoic acid permitted to crystallize out and the mixture filtered off and washed with about 50 parts of ice water. The filter cake, 20 which weighs 4.7 parts, has a melting point of 121-122° C. and represents benzoic acid of high purity. The recovery is 94%.

25 A mixture containing similar amounts of naphthalic and naphthoic acids is subjected to the same treatment using, of course, the corresponding amount of sodium carbonate. Excellent recovery of naphthoic acid of high purity is obtained and the filtrate contains monosodium naphthalate contaminated only 30 with a very little naphthoic acid.

Example 2

35 A mixture of benzoic and phthalic acids such as that described in Example 1 is completely neutralized in hot water solution by adding 15.9 parts of sodium carbonate and then sufficient N/10 sodium hydroxide to produce faint alkalinity to litmus. The solution is cooled and 10% sulfuric acid is added in 40 an amount equivalent to 9.7 parts of 100% H_2SO_4 , constituting 97.5% of the amount of mineral acid necessary to liberate the benzoic acid and convert the phthalate to the primary salt. The mixture is chilled and filtered as in Example 1, the benzoic acid cake obtained being 4.55 parts, which corresponds to a recovery of 91%.

45 The phthalic acid can be recovered from the sodium acid phthalate by acidification and cold filtration. A recovery of 88% is obtained and the product is of excellent quality and can be used to form further amounts of benzoic acid.

55 A similar procedure may be used in separating substituted phthalic acids from substituted benzoic acids, such as the chloro-, bromo-, nitro-, amino-, or halogen nitro-acids, and can also be applied to the separation of naphthalic acid from naphthoic acid or diphenic acid from phenyl-benzoic acid, using in each case the correct amount of sodium carbonate and sulfuric acid.

Example 3

65 A mixture containing about 1 part of

acrylic acid and 3 parts of maleic acid is dissolved in water and neutralized with sufficient sodium carbonate to convert the maleic acid into the primary sodium salt. The solution is then treated with ether or other organic solvent for acrylic acid, either by a batch process or by permitting the organic solvent to flow in countercurrent as described in connection with the separation of benzoic acid and phthalic acid in the patent to A. O. 70 Jaeger, No. 1,685,634 dated September 25, 1928.

75 If desired the water solution may be heated and part of the acrylic acid may be boiled off, leaving a residue which contains maleic and acrylic acids which may then be leached or washed with ether or other organic solvents for acrylic acid.

80 What is claimed as new is:

1. A method of separating polycarboxylic acids from the corresponding monocarboxylic acids, which comprises transforming the polycarboxylic acid into the primary salt while leaving the monocarboxylic acid in the free state and subjecting the mixture thus obtained to the action of a solvent in which the polycarboxylic salt and monocarboxylic acid show unequal solubility. 85

90 2. A method according to claim 1, in which a primary alkali metal salt of the polycarboxylic acid is formed. 95

95 3. A method according to claim 1, in which a mixture of the acids is subjected to partial neutralization by an alkali in order to form the primary salt of the polycarboxylic acid. 100

100 4. A method according to claim 1, in which the two acids are aromatic carboxylic acids.

105 5. A method of separating a polycarboxylic acid from its corresponding monocarboxylic acid which does not possess high solubility in water, which comprises forming a primary water soluble salt of the polycarboxylic acid and separating the mixture thus obtained by filtering an aqueous dispersion at a temperature at which the monocarboxylic acid is 110 relatively insoluble in water.

110 6. A method according to claim 5, in which the primary salt formed is an alkali metal salt.

115 7. A method according to claim 5, in which the mixture of poly- and monocarboxylic acids in aqueous dispersion are subjected to partial neutralization by an alkali in amount sufficient to form the monoalkali metal salt of the polycarboxylic acid. 120

120 8. A method according to claim 5, in which the acids are aromatic carboxylic acids.

125 9. A method of separating a phthalic acid from the corresponding benzoic acid, which comprises forming a water soluble primary salt of the phthalic acid and subjecting the mixture thus formed to separation by means of water at a temperature at which the benzoic acid is not readily soluble in water.

130 10. A method according to claim 9, in which

the primary salt of the phthalic acid is a monoalkali metal salt.

11. A method according to claim 9, in which the primary salt of the phthalic acid is formed by neutralization of a mixture of the phthalic and benzoic acids with just sufficient alkali to form the monoalkali metal salt of the phthalic acid.

12. A method of separating phthalic acid from benzoic acid, which comprises forming a water soluble primary salt of phthalic acid and subjecting the mixture thus formed to separation by means of water at a temperature at which benzoic acid is not readily

15 soluble in water.

13. A method according to claim 12, in which the primary salt of the phthalic acid is a monoalkali metal salt.

14. A method according to claim 12, in which the primary salt of the phthalic acid is formed by neutralization of a mixture of the phthalic and benzoic acids with just sufficient alkali to form the monoalkali metal salt of the phthalic acid.

25 Signed at Pittsburgh, Pennsylvania, this 4th day of April, 1929.
